UNITED STATES PATENT OFFICE.

JOHN B. HERGET AND ALBERT F. WALLOCH, OF SEATTLE, WASHINGTON.

AIRCRAFT FLIGHT CONTROL.

Application filed June 16, 1926. Serial No. 116,398.

This invention relates to flight controlling devices for air craft and hydroplanes; and its object is to provide improved means which are actuated by movements of the pilot's feet 5 for regulating the rudder ailerons and elevators to direct and control the flight of a vehicle of the air in a more convenient, expeditious, and reliable manner than hitherto.

In flight controlling devices at present in 10 use it is generally requisite that the operator employ both his hands and feet.

Such use of the hands for flight control purposes is dispensed with by our invention, leaving the hands at all times free for other 15 uses such, for example, as regulating the engine's throttle, sparking appliances and shutters.

To this end, we provide flight controlling means including a rudder-bar which is arranged 20 for oscillatory movements about horizontal and vertical axes and carrying foot actuated devices which are arranged and connected to the rudder, elevator and ailerons, in a manner to permit their being used either 25 singly or collectively as may be deemed desirable for controlling the vehicle when in flight.

The invention further consists in the novel 30 construction, adaptation and combination of parts hereinafter described and claimed.

In the accompanying drawings,—

Figure 1 is a plan view of a portion of an 35 aeroplane with an embodiment of the present invention applied thereto; and Fig. 2 is a longitudinal vertical section of the same, including a wing member and the associated aileron not shown in Fig. 1. Fig. 3 is a rear elevational view of flight control devices exemplified in an embodiment of the invention 40 now preferred by us, the several parts of the control being shown in their neutral positions; Fig. 4 is a side elevational view with parts in section, said section being taken on the line 4—4 of Fig. 3; Fig. 5 is a fragmentary 45 sectional view taken substantially on the line 5—5 of Fig. 4, the pivot shaft for the rudder-bar being shown in plan, and the rudder-bar in an adjusted position different from that in which it is illustrated in the preceding views; 50 and Fig. 6 is a vertical section taken on the line 6—6 of Fig. 5.

In said drawings, the reference numeral 10

represents, generally, the body of an aeroplane depending from a wing member 11 (Fig. 2) which is provided with an aileron 12. 55

A rudder 13, an elevator 14 and a tail-skid 15 are provided at the rear end of said body and are operatively connected therewith as usual.

All of the above described parts are or may 60 be of any known or suitable construction and arrangement.

According to the present invention, we secure to the aeroplane's body structure and within the cockpit 16 thereof (a standard 17 having a horizontal journal-bearing 18 for a pivot shaft 19 which is disposed longitudinally of the body. This pivot shaft is provided with a bifurcated rear end which protrudes 70 from the standard, as shown; the bifurcations 20 being spaced apart to receive therebetween the central portion 21 of a transversely arranged bar member, the end portions 22 of which are cylindrical.

Said bar member, or rudder bar as it will 75 be hereinafter designated, is fulcrumed centrally of its length to said pivot shaft by means of a tubular pivot 23 fitting in axially aligned holes provided in the central portion 21 of the rudder bar and in the bifurcations 80 20 of the pivot shaft. The axis of the pivot 23 is disposed at right angles to the axis of the cylindrical portion 19 of the shaft, or nearly so.

From the foregoing description it is apparent 85 that the pivot 23 taken with the pivot shaft connection constitute a universal joint connection for the rudder-bar with respect to the supporting standard 17.

Rotatively mounted upon the cylindrical 90 end portions 22 of the rudder-bar are sleeves 24. Adjacent to their outer extremities, said sleeves have rigidly secured thereto plates 25 to receive the right and left feet, respectively, of the pilot occupying a seat, such as 95 26 (Figs. 1 and 2) provided within the cockpit to the rear of the control. The plates 25 or foot plates, as they will be termed hereinafter, are advantageously provided with heel supporting flanges 25¹ so as to provide 100 at all times a comfortable rest for the feet of the pilot.

In proximity with the respective foot plates, the sleeves 24 are provided with cir-

cumferential flanges 27, or equivalent devices, serving as end bearings for independently rotatable collars 28, one for each sleeve.

As shown, the collars 28 are provided with 5 eye elements 29 whereby the collars are connected to the forward ends of cables 30 whose other ends are connected to the yoke arms 13¹ of the rudder for swinging the latter to one side or the other responsive to the rudder 10 bar 21—22 being rotatively moved about the axis of the pivot 23.

The tail skid 15 is arranged to be operated from the rudder-operating cables 20 through the medium of branch cables, such as 30¹ 15 (Fig. 2) connected to the tail skid yoke in a known manner.

Rigid with and depending from the pivot shaft 19 is an arm 31 having secured thereto the ends of cables 32 and 32¹ which are led 20 laterally to guide pulleys 33 and 33¹ and thence upwardly to make suitable connections with the aileron operating arms 12¹ for regulating the angularity of the ailerons with respect to the wing 11 when the arm 31 is 25 caused by foot actuated movements of the rudder bar to be swung pendulum-like toward one side or the other.

It is to be noted that such swinging movements of the aileron controlling arm 31 is 30 effected through the medium of the pivot shaft 19 when influenced by the rudder bar being oscillated in a plane at substantially right angles to the plane of its movement for governing the rudder.

35 Secured to said rudder bar between the sleeves 24 are upwardly directed complementary bracket arms 34 serving to support a pin 35 upon which are mounted, for individual rotary movements, two sheaves 36 and 36¹ for cables 37 and 37¹, respectively; the extremities, as 37² (Fig. 4) for instance, of the cables being secured to the respective sheaves.

40 The cables 37, 37¹ extend from their operating sheaves 36, 36¹ through the aperture of 45 the tubular pivot 23 to guide pulleys 38, 38¹ which direct the cables to arms 14¹ of the elevator 14; for adjusting the same. The guide pulleys 38, 38¹ are journaled upon a pin 39 which is supported by a bracket 40 rigid with the arm 31.

45 The mounting of the cable operating sheaves 36, 36¹ which are carried by the bar arms 34, and that of the guide pulleys 38, 38¹ which are carried by the pivot-shaft arm 31 cause 50 said sheaves and the pulleys to be bodily revolved as a unit about the axis of the pivot shaft when the rudder-bar 21—22 is moved in a substantially vertical plane. As shown, one or the other of the operating sheaves 36, 36¹ 55 is adapted to be rotated selectively upon the pin 35 by means of the associated foot plates 25 rotating the respective sleeves 24 and the arms 41, which are rigid with the sleeves.

50 Each arm 41 is provided with a slot, such 60 as 42 (Fig. 4), to receive a crank pin as

48, provided on the respective sheaves whereby a rotary movement of either of the sleeves, (as effected by a foot plate) will impart rotary movement to a sheave 36 or 36¹ for actuating the cable 37 or 37¹ to set the elevator. 70

The operation of our improved flight control is extremely simple: The rudder-bar 21—22 being oscillated in a substantially horizontal plane about its pivot 23 for regulating the rudder 13, and in a substantially vertical plane about the axis of the pivot shaft 19 for regulating the ailerons but for regulating the elevator the sleeves 24 are rotated upon the respective arms of the rudder bar. 75

All of the operations of our improved flight 80 control are performed by means of the pilot's foot and leg movements, (applied either separately or in combination, through the medium of the foot plates 25.

The regulating of any one of the flight 85 controlling devices above named—rudder, elevator or ailerons—may be done independently of the others or they may be operated in pairs, or all together, as may be required or deemed desirable either for steering, balancing or stabilizing the aeroplane. 90

The manner of using our improved control and its advantages will, it is thought, be understood from the foregoing description.

While we have described specifically an 95 embodiment of the invention now preferred by us, we do not wish to be understood as confining ourselves thereto except as limited by the scope of the following claims.

What we claim, is,—

1. In an aeroplane having an aileron and an elevator, a rudder-bar arranged for movement upon a fulcrum having its axis longitudinal of the aeroplane, an arm depending from said fulcrum, sleeves rotatably mounted upon the arms of the rudder-bar, cable connections between said arms and the aileron for regulating the latter when the rudder-bar is moved about said fulcrum axis, sheaves carried by said rudder-bar, cable connections between said sheaves and the elevator, sheave operating means carried by said sleeves, and foot plates rigid with the respective sleeves for effecting the rotation of the same to impart rotary movement to the sheaves for regulating the elevator, said foot plates also serving to effect oscillatory movement to the rudder-bar and the fulcrum arm for regulating the aileron. 115

2. In an aeroplane having an aileron and an elevator, a flight control therefor, said control having a rudder-bar fulcrumed at its midlength for movement in a substantially vertical plane, an arm extending below said rudder-bar, arms extending above the rudder-bar, all of said arms being movable as a unit with the rudder bar, sheaves carried by the upper of said arms, guide pulleys carried by the lower arm, cables connected to the respective sheaves and passing about the 120 125 130

guide pulleys to said elevator, foot controlled means rotatable upon the rudder bar at opposite sides of its fulcrum for actuating said sheaves to operatively move the elevator, said foot controlled means also serving to impart oscillatory movement to the rudder-bar and the first named arm, and operative connection between the last referred to arm and the aile-

ron for adjustably moving the same responsive to the foot impelled movement of the rudder-bar. 10

Signed at Seattle, Washington, this 17th day of May, 1926.

JOHN B. HERGET.
ALBERT F. WALLOCH.
